CLAIM

The ornamental design for a fluid flow conducting tube for a heat exchanger, as shown and described.

DESCRIPTION

FIG. 1 is an isometric view of a fluid flow conducting tube for a heat exchanger;

FIG. 2 is an elevational view of either end of the fluid flow conducting tube of FIG. 1;

FIG. 3 is an elevational view of either side of the flow conducting tube of FIG. 1;

FIG. 4 is a top view of the fluid flow conducting tube of FIG. 1; and,

FIG. 5 is a bottom view of the fluid flow conducting tube of FIG. 1.

FIG. 1

FIG. 2

FIG. 3

FIG. 4

FIG. 5
